CARL F. DOERSCHUK, OF CLEVELAND, OHIO.

ANTICREEPING DEVICE FOR RAILS.

1,175,722.

Specification of Letters Patent. Patented Mar. 14, 1916.

Application filed March 18, 1914. Serial No. 825,542.

To all whom it may concern:

Be it known that I, CARL F. DOERSCHUK, a citizen of the United States, and a resident of Cleveland, county of Cuyahoga, 5 State of Ohio, have invented a new and useful Improvement in Anticreeping Devices for Rails, of which the following is a specification, the principle of the invention being herein explained and the best mode in which 10 I have contemplated applying that principle, so as to distinguish it from other inventions.

The present improvements relating as indicated to anti-creeping devices for rails 15 are particularly adapted to be attached to the ties upon which the rails are laid and to then engage the rails to prevent the latter from longitudinal movement upon the passage of a train. The prime requisites of 20 such a device are simplicity and security of attachment. The present invention has been designed to provide as simple a construction as possible and one which may be readily attached to the rail.

25 To the accomplishment of the foregoing and related ends, said invention, then, consists of the means hereinafter fully described and particularly pointed out in the claims.

30 The annexed drawings and the following description set forth in detail certain mechanism embodying the invention, such disclosed means constituting, however, but one of the various mechanical forms in which 35 the principle of the invention may be used.

In said annexed drawings:—Figure 1 is a view in perspective showing a portion of a rail attached to a tie where it is securely held by means of any improved anchor; Fig. 40 2 is a side elevation of one part of the rail anchor shown in Fig. 1; Fig. 3 is a view in perspective of the locking means for such rail anchor; Fig. 4 is a perspective view similar to Fig. 1 but showing a modified 45 form of the invention; Fig. 5 is an end elevation of the rail and anchor shown in Fig. 4; Fig. 6 is a bottom plan view of the rail anchor shown in Figs. 4 and 5, and Fig. 7 is a perspective view similar to Fig. 4 but 50 looking down upon the rail instead of up, as in the former figure.

Referring to Figs. 1, 4 and 7, there is shown a portion of the tie 1 upon which rests a rail 2 which may be suitably attached to such tie by the usual track spikes, etc. (not shown). The rail 2 is of the usual

construction being provided with a base 3 having the usual laterally extending flanges.

Upon most railroads each track is intended for traffic in a single direction, and consequently the longitudinal thrust upon the rails acts always in the same direction. In time this thrust tends to move the rails longitudinally, and it is to prevent this movement, which has in the past often 60 caused accidents, that the present rail anchors are provided.

Referring now to Fig. 1, the preferred form of my rail anchor will be seen. The anchor comprises a rail-receiving body 70 member, or shoe, 7 which is adapted to rest upon the tie and is provided at one end with a downwardly extending flange 8 which rests against the side of such tie. This end flange 8 is preferably provided with sharpened engaging members or wedges 9 which enter the wooden tie and maintain the body member in its proper position with respect to the same. Two upwardly extending rebent arms 16 are preferably integrally connected to the body member 7, the upper or adjacent ends of such arms being spaced a less distance apart than the width of the base of the rail, thus making it necessary to turn the rail in order to introduce the same 75 between such arms. The upper or horizontal portions 15 of the arms 16 are spaced a slight distance above the base of the rail when the latter rests upon the body member 7.

The preferred type of means for locking the rail to the shoe are shown in Fig. 3. In this figure there is shown a U-shaped loop 18 provided with parallel spaced arms 17 between which there is interposed a pin or 80 plate 19 having a wedge-shaped portion 20 lying just beyond the spaced ends of the arms 17. This pin 19 is provided with a laterally projecting lug 22 and if desired the adjacent faces of the ends of the arms 17 85 may be beveled slightly as at 21 to facilitate the introduction of the wedge-shaped portion 21 of the pin 19. It will be noticed that the bottom arm of the loop 18 is provided with a notch 25 adapted to fit snugly over 90 the edge of the base of the rail. Between each arm 16 and the adjacent portion of the base 3 of the rail there is introduced the assembled locking device, such as is shown in Fig. 3. The notch 25 in such locking device engages over and against the edge of 95 the base of the rail, thus centrally position-

ing the same with respect to the anchor 7 and the arms 16. When the locking device shown in Fig. 3 is thus positioned between the arm 16 and the rail base, the head end 5 of the loop 18 is struck a sharp blow thus driving the loop longitudinally along the rail beneath the arm 16. Movement of the pin or plate 19 is prevented by reason of the projecting lug 22 on the same, which 10 engages against the side of the arm 16, thus causing relative movement between the loop and the pin and spreading the two arms 17 of the loop by reason of the introduction therebetween of the wedge-shaped portion 15 20 of the pin 19. The final position of the locking means is shown in Fig. 1. A considerable force is thus exerted upon the rail base by the locking wedge which is held beneath the arms 16, this force being sufficient 20 to prevent the rail from moving under the thrust of passing trains. In order to prevent movement of the rail in either direction, should the track be used for traffic in both directions, the anchors may be directed 25 in opposite directions upon adjacent ties.

In Figs. 4 to 7 inclusive I show a modified form of the invention in which the body member 7 of the anchor is provided with a serrated wedge 26 adapted to enter the tie 30 and with a forwardly extending curved wedge 10 adapted to lie beneath and in contact with the base 3 of the rail. I provide a clamp 4 which may be driven over the rail and wedge 10, such clamp having outwardly extending sides 5 and inwardly extending arms 6, the latter being adapted to extend over the rail base 3. The wedge 10 is provided with curved sides 11 which are adapted to be slidably engaged by the slides 35 40 5 of the clamp, thus centrally positioning such clamp with respect to the rail upon movement of the clamp into its locking position. It will of course, be understood that the anchors shown in these figures may be 45 oppositely directed upon adjacent ties in order to prevent any tendency toward loosening under the action of the passing train.

In most cases the rail anchors will be used on tracks in which the traffic moves in a 50 single direction, in which event each anchor is tightened by the passage of each train. This feature eliminates the necessity of inspection of the anchors as the latter when once applied can never become loose except 55 upon reversal of the traffic.

Other modes of applying the principle of my invention may be employed instead of the one explained, change being made as regards the mechanism herein disclosed, 60 provided the means stated by any of the following claims or the equivalent of such stated means be employed.

I therefore particularly point out and distinctly claim as my invention:—

65 1. In a rail anchor, the combination of a

rail receiving base member provided with sharpened tie-engaging means, arms connected to said member and adapted to extend over the base of a rail, and locking wedge means interposed between one of said arms 70 and such base of said rail, thereby rendering said arm operative to grip such base of said rail.

2. In a rail anchor, the combination of a rail receiving base member adapted to engage a tie, arms connected to said member and extending over either side of the base of such rail, and wedge means adapted to be driven between one of said arms and the rail, said means comprising a plurality of 80 longitudinally disposed members co-operating to space said arm from such rail.

3. In a rail anchor, the combination of a rail receiving base member adapted to engage a tie, arms connected to said member 85 and extending over either side of the base of such rail, and wedge means adapted to be driven between one of said arms and the rail, said means comprising two longitudinally disposed members mounted one within the other, both such members co-operating 90 to space said arm from such rail.

4. In a rail anchor, the combination of a rail receiving base member adapted to engage a tie, arms connected to said member 95 and extending over either side of the base of such rail, and wedge means adapted to be driven between one of said arms and the rail, said means comprising two co-operative wedging members adapted, when driven between said arm and such rail to relatively move to increase their combined transverse depth on either side of said arm to a distance greater than the distance from said arm to such rail.

5. In a rail anchor, the combination of a rail receiving base member adapted to engage a tie, arms connected to said member and extending over either side of the base of such rail, and wedge means adapted to be 110 driven between one of said arms and the rail, said means comprising two contacting members, one of said members being tapered longitudinally, said members in one longitudinal relation being of less thickness at 115 one end than the distance from said arm to such rail but in another relation being of greater thickness at either end than such distance, one of said members being provided with means causing relative movement 120 between said members into such last named relation when said members are driven between said arm and such rail.

6. In a rail anchor, the combination of a rail receiving base member provided with 125 sharpened tie-engaging means, arms integrally connected to said member and adapted to extend over the base of a rail, and locking wedge means interposed between said arms and such base of said rail, thereby 130

rendering said arms operative to grip such base of said rail.

7. In a rail anchor, the combination of a rail receiving base member adapted to rest upon and against one side of a tie, said member being provided with sharpened wedges adapted to engage the side of such tie, curved arms integrally connected to said member and extending over the base of a rail, and locking wedge means interposed between said arms and such base of said rail, thereby rendering said arms operative to grip such base of said rail.

8. In a rail anchor, the combination of a rail receiving base member adapted to engage a tie, arms connected to said member and extending over either side of the base of such rail, said arms being spaced from such base, and self-locking wedge means interposed between one of said arms and such base of said rail, said means comprising a looped member having two parallel spaced arms, and a wedge shaped expanding pin interposed between such spaced arms and provided with a lateral projection adapted to engage against said arms on said base member.

9. In a rail anchor, the combination of a rail receiving base member adapted to engage a tie, arms connected to said member and extending over either side of the base of such rail, said arms being spaced from such base, and self-locking wedge means

interposed between said arms and such base of said rail, said means comprising a looped member having two parallel spaced arms, and an expanding pin interposed between such parallel spaced arms and having an enlarged portion lying initially beyond the ends of such arms, and a lateral projection at its other end adapted to engage against said arm connected to said base member upon longitudinal movement of said looped member, thereby preventing further movement of said pin and causing the enlarged portion of the same to spread such arms of said looped member.

10. In a rail anchor, the combination of a rail receiving base member adapted to rest upon and against one end of a tie and provided with sharpened wedges adapted to engage the side of such tie, a wedge integrally attached to said member and extending beneath the base of such rail, and a clamp slidably engaging over the base of such rail and said wedge and having arms extending over the base of such rail, such arms being caused to grip the rail upon movement of said clamp along said wedge.

Signed by me, this 16th day of March, 1914.

CARL F. DOERSCHUK.
